Primary Examiner — Darlington Ly*Assistant Examiner* — Katherine A Holbrow(74) *Attorney, Agent, or Firm* — Brake Hughes Bellerman LLP(57) **CLAIM**

The ornamental design for a display screen with graphical user interface for live video sharing, as shown and described.

DESCRIPTION

The FIGURE is a front view of a display screen with graphical user interface for live video sharing, showing the new design.

The broken line showing of the device, display screen and graphical user interface are included for the purpose of illustrating environmental structure and portions of the article and form no part of the claimed design.
